[57] CLAIM

The ornamental design for a door handle, as shown and described.

DESCRIPTION

FIG. 1 is a perspective view of a door handle showing my new design;

FIG. 2 is a front elevational view thereof;

FIG. 3 is a top plan view thereof, the bottom plan view being a mirror image;

FIG. 4 is a rear elevational view thereof;

FIG. 5 is a right end elevational view thereof;

FIG. 6 is a left end elevational view thereof;

FIG. 7 is a perspective view of a second embodiment of the design of FIG. 1, the only difference being that the door handle distal end member has a wood-grain surface; and

FIG. 8 is a front elevational view thereof;

FIG. 9 is a top plan view thereof, the bottom plan view is a mirror image;

FIG. 10 is a rear elevational view thereof;

FIG. 11 is a right end elevational view thereof;

FIG. 12 is a left end elevational view thereof;

FIG. 13 is a perspective view of a third embodiment of the design of FIG. 1, the only difference being that the door handle distal end member is transparent;

FIG. 14 is a front elevational view thereof;

FIG. 15 is a top plan view thereof, the bottom plan view is a mirror image;

FIG. 16 is a rear elevational view thereof;

FIG. 17 is a right end elevational view thereof; and,

FIG. 18 is a left end elevational view thereof.

The broken line showing of the escutcheon is for illustrative purposes only and forms no part of the claimed design.
